UNITED STATES PATENT OFFICE.

ROBERT KENNEDY DAWSON, OF GUELPH, ONTARIO, CANADA.

CENTER HUB FOR REVOLVING CHAIRS.

1,379,969.

Specification of Letters Patent. Patented May 31, 1921.

Application filed January 28, 1921. Serial No. 440,698.

To all whom it may concern:

Be it known that I, ROBERT KENNEDY DAWSON, of the city of Guelph, in the county of Wellington, in the Province of Ontario, Canada, have invented certain new and useful Improvements in Center Hubs for Revolving Chairs, of which the following is a specification.

My invention relates to improvements in center hubs for revolving chairs and the object of the invention is to devise simple means for connecting the chair legs to the center hub in such a way that the resistance to outward strain or tendency to pull apart is provided just at the required point to counteract this tendency and it consists essentially of an upper and lower plate, a tubular connector extending between the plates, the lower plate being provided with radial arms, and lug projections extending upward from the lower plate in broad V-form providing interspaces diverging outwardly toward the center of the hub, and chair legs provided with dovetailed ends fitting between the upper and lower plates and having recesses in the lower portion thereof into which the side arms of the V-shaped lug projections fit and securing screws extending through the upper and lower plates into the chair legs as hereinafter more particularly described by the following specification.

Figure 1 is a perspective view of my center hub showing leg portions connected thereto. Fig. 2 is a plan view, the right hand portion being on a plane coinciding with the upper edges of the chair legs and the left hand portion on a plane coinciding with the upper edges of the lug projections of the lower center hub plate.

Fig. 3 is a perspective detail of one of the V-shaped lug projections and a fragmentary portion of the lower center hub plate to which it is connected. Fig. 4 is a fragmentary perspective detail of the portion of the chair leg adjacent to the lower center hub plate showing the receiving recess for the lug projection shown in Fig. 3.

Fig. 5 is a sectional detail showing the means for securing the tubular connector to the upper and lower center hub plates.

In the drawings like characters of reference indicate the corresponding parts in each figure.

1, 2, 3 and 4 are chair leg portions which

radiate from the center hub hereinafter described. Each chair leg portion is provided at its inner end with a ratchet-shaped recess 5 located at each side thereby forming a dove-tailed inner end 6. In each side of each dove-tailed portion 6 and extending upwardly from its lower edge is located a recess 7. The center hub comprises an upper circular plate 8 provided with orifices 9 through which screws 10 extend into the leg portions 1, 2, 3 and 4. A lower plate 11 is provided with radiating arms 12 which are preferably provided with edge flanges 13. The plate 11 is also provided with orifices 14, the edge of which is turned upward as indicated at 15 which upturned edge is forced into the leg portions 1, 2, 3 and 4 by the screws 16 as the plate 11 is drawn against the leg portion by the screws. The orifices 9 of the plate 8 may be provided with similar turned portions which are forced by the screws 10 into the upper edge of the leg portions 1, 2, 3, or 4. 17 are rectangular orifices formed in the body of the plate 11. 18 are broad V-shaped plate projections provided with lugs 19 which extend through the orifices 17 being riveted or otherwise suitably secured therein. The lug projections 18 are secured to the lower center hub plate 11 between each pair of the leg portions 1, 2, 3 and 4 so that each side arm of each V-lug projection fits into a recess 7 as clearly indicated in Fig. 2.

It will thus be seen that when the weight is brought to bear upon the legs of the chair, the tendency is for that portion of the chair leg in proximity to its upper edge to be forced inward and that portion in proximity to the lower portion of the chair leg to pull outward.

It will therefore be seen that nothing is required to counteract any outward pull of that portion in proximity to the upper edge which portion forms a fulcrum around which the chair leg tends to swing vertically. This tendency is counteracted by the lug projections 18 fitting within the recesses 7. The lug projections form an inter-space which is contracted toward its outer end so as to clearly hold that portion of the leg fitting therebetween from pulling outward.

21 are segmental spacing pieces which fit between the upper and lower plates 8 and 11 and in the recessed portion of the chair leg and also against the outer face of the lug projections 18. 22 is a tubular connection

extending between the plates 8 and 11 and through orifices therein. The upper end edge of the connector is rolled out over the edge of the orifice in the plate 8 and the 5 lower end of the connector is reduced at 23 to fit the orifice 24 in the plate 11.

It will thus be seen that I have provided a very simple, strong and durable construction which is reinforced exactly at the point 10 needed to prevent the legs of the chair and center hub breaking apart.

What I claim as my invention is:

1. A center hub for revolving chairs, comprising an upper plate and a lower opposing plate suitably connected together, chair legs 15 extending at their inner ends between the opposing plates and having recesses at the lower portion thereof and lug projections

extending upwardly from the lower plate and fitting the recesses and adapted to resist the tendency to outward pull of the chair leg when downward pressure is brought to bear upon the center hub. 20

2. A center hub for revolving chairs, comprising an upper and lower plate, chair legs 25 the inner ends of which are provided with dove-tailed portions extending between the upper and lower plates and having recesses in the lower portion of each side, and lug 30 projections of broad V-shaped form secured to the lower plate between each pair of chair legs so that the arms of the V fit within the recesses of the opposing sides of each pair of adjacent chair legs.

ROBERT KENNEDY DAWSON.
